Primary Examiner — Mary Ann Calabrese*Assistant Examiner* — Catherine Ho(74) *Attorney, Agent, or Firm* — Allen Dyer Doppelt & Gilchrist, PA(57) **CLAIM**

The ornamental design for a vehicle-mounted sign, as shown and described.

DESCRIPTION

FIG. 1 is a bottom, right, rear perspective view of a vehicle-mounted sign, showing my new design;

FIG. 2 is a bottom, right, front perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken line portion of the figure drawings is included to show portions of the article that form no part of the claimed design.

1 Claim, 5 Drawing Sheets(56)
